[57] CLAIM

The ornamental design for a lantern housing, as shown and described.

DESCRIPTION

FIG. 1 is a perspective view of a lantern housing showing my new design; the oblique line shading indicating translucent surfaces;

FIG. 2 is a perspective view of a second embodiment of my design;

FIG. 3 is a side elevational view thereof on an enlarged scale, and

FIG. 4 is a top plan view thereof on an enlarged scale. The second embodiment differs from the first only by omission of the translucent side panels.
